UNITED STATES PATENT OFFICE

2,286,789

INTEGRAL HIGH PRESSURE LAMP AND
STARTING CIRCUIT THEREFOR

Edward Charles Dench, South Orange, N. J., assignor to Westinghouse Electric & Manufacturing Company, East Pittsburgh, Pa., a corporation of Pennsylvania

Application May 1, 1940, Serial No. 332,626

2 Claims. (Cl. 176—124)

The present invention relates to electric discharge lamps and more particularly to high pressure high intensity mercury arc lamps and starting circuits therefor.

In order to start lamps of this particular type, a comparatively high starting voltage is required which has necessitated the employment of auxiliary equipment of a cumbersome nature interposed between the commercial source of supply of the customary potential of 115 to 230 volts and the lamp.

To facilitate starting of these lamps it has been the usual practice to employ a starting electrode disposed adjacent one of the main discharge supporting electrodes and between which a local discharge occurs upon the application of a relatively low potential. This local discharge accordingly ionizes the gaseous medium in the lamp within a few seconds, causing breakdown of the lamp at a much lower voltage than otherwise. Again, however, the necessity for a starting electrode not only increases the manufacturing cost of the lamp, but decreases very little the cost and weight of the auxiliary starting equipment.

It is accordingly an object of the present invention to provide a discharge lamp of the high pressure mercury vapor type wherein the essential portions of the auxiliary starting equipment are enclosed in an envelope with the lamp so as to form an integral unit.

Another object of the present invention is the provision of a discharge lamp of the high pressure mercury vapor type wherein portions of the necessary starting equipment for the lamp are enclosed within the envelope for the lamp and so connected in a starting circuit as to facilitate starting of the lamp without any starting electrode being required.

Another object of the present invention is the provision of a discharge lamp of the high pressure mercury vapor type which can be readily started at lower voltage than heretofore necessary and without a starting electrode, thus giving a higher power factor operation of the system.

A further object of the present invention is the provision of a discharge lamp of the high pressure mercury vapor type wherein a protective element is provided in the envelope for the lamp to prevent excessive voltage from destroying other portions of the starting equipment and which also facilitates restarting of the lamp upon a failure of power.

Still further objects of the present invention will become obvious to those skilled in the art by

reference to the accompanying drawing wherein:

Fig. 1 is an elevational view partly in section of a high intensity high pressure mercury vapor lamp constructed in accordance with the present invention;

Fig. 2 is a cross-sectional view taken on the line II—II of Fig. 1 and looking in the direction indicated by the arrows;

Fig. 3 is a diagrammatic illustration of the starting circuit for the lamp as shown in Figs. 1 and 2;

Fig. 4 is a diagrammatic illustration which the starting circuit of Fig. 3 may take, and

Fig. 5 is a diagrammatic illustration of a modification which the lamp and starting circuit may also take.

Referring now to the drawing in detail, the device as shown in Fig. 1 comprises an enclosing envelope 5 of suitable vitreous material, such as 20 glass or the like, transparent to light; and, if desired, it may be of quartz or other ultra-violet pervious material. Appropriately secured to the envelope is a base 6 of the usual type to enable the device to be screwed into a socket.

25 The envelope 5 is provided with a mount comprising a reentrant stem 7 having the customary press portion 8. A pair of leading-in conductors 9 and 10 of suitable metal are sealed to the press and connected to the center contact and shell of 20 the base 6. As will be noted, the leading-in conductors 9 and 10 are of rod-like form and widen out immediately above the press portion and extend in parallel relation longitudinally of the enclosing envelope 5.

35 A pair of bridges 12 and 13 of a suitable insulating material, such as mica or the like, tie the leading-in rods together for the purpose of forming a rigid mount for a discharge lamp 14. This lamp 14 as shown is of the high pressure

40 type and comprises an envelope 15 of vitreous material capable of withstanding the high temperature of operation, such as quartz or the like, and provided with a pair of electrodes 16 and 17 between which a discharge occurs when a suitable potential is applied thereto. After evacuation

45 of the envelope 15 through an exhaust tip 18, it is filled with an ionizable medium, such as mercury, together with an inert gas, such as argon, neon, or the like, to facilitate starting

50 with the pressure of the ionizable medium during operation ranging between 5 and 10 atmospheres.

The lamp 14 as shown has the customary elongated tapering seal at each end to which the leading-in wire for each electrode is sealed. This elongated end passes through openings 20 pro-

vided in the bridges 12 and 13, which thus suspends the lamp 14 between the latter in firm engagement therewith. Each bridge is in turn provided with a pair of eyelets 22 and 23 secured thereto having annular portions projecting normal to the surface through which the rod-like leading-in conductors 9 and 10 extend; and, after the bridges are in proper position relative to the lamp 14 and the leading-in conductors, the eyelets are secured to the latter in any suitable manner, such for example as by welding.

Upon securing the bridges in place, a flexible lead 24 is welded to the leading-in conductor 9 and to the lower electrode 17, and in a similar manner a flexible lead 25 connects the upper electrode 16 to the other leading-in conductor 10 to complete the electrical connection from the base 6 to the opposite electrodes 16 and 17 of the lamp 14. To prevent condensation of the vaporizable material at the coolest portions of the lamp 14, which is naturally back of the electrodes, a heat-reflecting shield 26 is positioned at each end of the lamp which may be secured to the insulating interconnecting bridges, such as by tabs or the like.

As will be noted, these shields are of conical form and may be of metal such as nickel, iron, or an alloy with the ends of the high pressure discharge lamp resting therein with a slight spacing between the greater area of the shield and the lamp to reduce the thermal conductivity therebetween, which thus conserves the heat to prevent condensation of the ionizable medium rearwardly of the electrodes and at the same time preventing the shields from becoming so hot as to melt the envelope 15.

In order to initiate a discharge between the electrodes 16 and 17 of the high pressure discharge lamp 14, auxiliary apparatus is mounted within the enclosing envelope 5. For example, as shown in Figs. 1 and 2, a gaseous electric relay device 27 is supported by a pair of semi-circular clamps 28, the ends of which are welded to the respective leading-in and supporting wires 9 and 10. This gaseous electric relay device is of the type shown and claimed in U. S. Patent 2,200,443, issued May 14, 1940, to Edward C. Dench and assigned to the same assignee as the present invention.

Since the gaseous electric relay device per se forms no part of the present invention, it is believed unnecessary that the same be herein described in detail. It should suffice to say that it comprises an envelope provided with an ionizable medium therein and a pair of electrodes, one of which is a heat-responsive element adapted to emit electrons when heated. Upon the application of a potential from the customary source of 115-230 volts, a glow discharge occurs between the electrodes which heats the heat-responsive element. This latter element moves to cause engagement of the electrodes with extinguishment of the discharge.

As shown in Figs. 1 and 2, the heat-responsive element 29 is connected by a conducting bar 30 to the leading-in conductor 9 and the remaining electrode 32 of the gaseous electric relay device is normally connected by means of a thermo-expansive or bimetallic element 33, one end of which is welded or otherwise secured to a support member 34. This support member is in turn welded or otherwise affixed to the leading-in conductor 10 and is provided with an insulated section such as a glass bead or the like 35 so that the support 34 forms no electrical connection with

the leading-in and supporting conductor 10. In order to electrically connect the thermo-expansive element 33 to the leading-in conductor 10 and at the same time limit the current, an impedance, such as a ballast resistor 36, is secured by welding or the like to the leading-in conductor 10 and to the insulated end of the support 34 which thus connects the same to the thermo-expansive element 33.

By reference now to Fig. 3, the electrical circuit thus formed by the auxiliary equipment within the enclosing envelope 5 is shown. The completed lamp is inserted in the usual type of socket and an inductance 37 is interposed between the source of supply L1—L2 of the customary domestic potential of 115-230 volts and one of the electrodes 17 of the high pressure discharge lamp 14. Thus upon closure of a suitable switch (not shown), a glow discharge occurs in the gaseous electric relay device 27 since the heat responsive electrode 29 is connected by the bar 30 directly to the leading-in conductor 9 and the remaining electrode 32 is connected by the thermo-expansive element 33 and impedance or ballast resistor 36 to the leading-in conductor 10.

Inasmuch as the gaseous electric relay device 27 and impedance 36 are in parallel with the lamp 14, they form a short-circuit for the high pressure discharge lamp 14 so that no current flows therethrough, particularly since the resistance thereof is much higher than the circuit including the gaseous electric relay device 27 and impedance 36.

The resulting glow discharge accordingly heats the heat-responsive element 29 causing engagement of the electrodes and extinguishment of the glow discharge, which thus connects the impedance 36 and inductance 37 across the source of supply L1—L2. Immediately following extinguishment of the glow discharge in the gaseous electric relay device 27, the heat responsive element 29 cools sufficiently to cause disengagement of the electrodes 29 and 32. At the instant of disengagement of the electrodes the inductance element 37 causes a high voltage surge to be impressed across the electrodes 16 and 17 of the high pressure discharge lamp 14 which accordingly ionizes the medium therein, causing the initiation of a discharge.

The current from the source of supply L1—L2 accordingly flows through the high pressure discharge lamp 14 with the result that the potential available across the electrodes 29 and 32 of the gaseous electric relay device is insufficient to again initiate a glow discharge, and the positive column discharge of the high pressure discharge lamp 14 also functions to short-circuit the gaseous electric relay device 27 and impedance 36.

Thus the gaseous electric relay device 27 remains inoperative so long as the discharge continues in the high pressure discharge lamp 14. Upon extinguishment of the high pressure discharge lamp 14, however, the gaseous electric relay device 27 will again perform its cycle of operation to initiate a discharge in the high pressure discharge lamp 14. The circuit thus far described is exactly as shown in Fig. 5. However, in order to prevent the heat generated by the high pressure discharge lamp 14 from inadvertently heating the heat-responsive element 29 of the gaseous electric relay device 27, the thermo-expansive element 33 is provided, as diagrammatically shown in Fig. 3.

In this particular modification and as shown in Figs. 1 and 2, the thermo-expansive element

33 normally connects the electrode 32 of the gaseous electric relay device 27 with the impedance or ballast resistor 36. During operation of the high pressure discharge lamp 14 a considerably high temperature is generated which accordingly heats the thermo-expansive element 33 causing it to flex in the manner shown in dotted lines in Figs. 2 and 3, which thus disconnects the gaseous electric relay device 27 from the impedance 36 and consequently from the leading-in conductor 10. Consequently, even should the high temperature of the high pressure discharge lamp 14 inadvertently heat the heat-responsive element 29 of the gaseous electric relay device 27, causing it to engage the remaining electrode 32, the high pressure discharge lamp 14 is not thereby short-circuited so as to extinguish the discharge, as might otherwise be the case in the arrangement shown in Fig. 5.

Naturally, the provision of the thermo-expansive element 33 is not always necessary inasmuch as the gaseous electric relay device may be disposed in the coolest portion of the enclosing envelope 5, such as shown in Fig. 1, so that it is not heated sufficiently by the high pressure discharge lamp 14 as to cause inadvertent operation of the heat-responsive element of the gaseous electric relay device 27.

In the circuit arrangement shown in Fig. 4 a modification is shown which is identical to that previously described with respect to Figs. 3 and 5, with the exception that an auto-transformer 38 is shown in lieu of the inductance 37 of Figs. 3 and 5.

It thus becomes obvious to those skilled in the art that a high pressure discharge lamp is herein provided wherein the essential portions of the auxiliary starting equipment are enclosed in a single envelope with the lamp so as to form an integral unit. Moreover, the auxiliary equipment is so mounted and connected to the lamp that a discharge is readily initiated without the necessity of an auxiliary starting electrode as heretofore required. Due to the construction herein disclosed the integral unit may be readily inserted in the customary sockets so as to be energized from the usual source of commercial potential.

Although several embodiments of the present invention have been shown and described, it is to be understood that still further modifications thereof may be made without departing from the spirit and scope of the appended claims.

I claim:

1. A high pressure gaseous discharge lamp comprising an enclosing envelope, a gaseous discharge lamp provided with electrodes and an ionizable medium therein supported within said envelope, leading-in conductors for supplying

electrical energy to the electrodes of said lamp, an impedance supported within said enclosing envelope, a gaseous electric relay device supported within said enclosing envelope provided with an ionizable medium therein and a pair of electrodes one of which is a heat-responsive element and between which a glow discharge occurs upon the application of a potential therebetween, and operable upon heating of said heat-responsive element by the ensuing glow discharge to cause extinguishment of the latter and to connect said impedance across said leading-in conductors to short-circuit said lamp, and said gaseous electric relay device being operable upon cooling of said heat-responsive element to interrupt the short-circuit of said lamp and to disconnect said impedance from across said leading-in conductors to cause a discharge between the electrodes of said lamp; and a thermo-expansive element normally connecting said impedance and said gaseous electric relay device and operable upon heating by said discharge lamp during operation thereof to disconnect said impedance and said gaseous electric relay device to prevent the heat from said lamp causing undesired operation of said gaseous electric relay device with inadvertent short-circuiting of said lamp.

2. A starting and operating circuit for a high pressure gaseous discharge lamp provided with electrodes and an ionizable medium therein comprising a source of electrical energy of the usual domestic potential, an inductance element connected to said source and to one of the electrodes of said lamp, an impedance adapted to be connected to said source, and a gaseous electric relay device provided with an ionizable medium therein and a pair of electrodes one of which is a heat-responsive element, and between which a glow discharge occurs upon the application of a potential from said source and operable upon heating of said heat-responsive element by the ensuing discharge to extinguish the latter and initially connect said impedance to said source and to short-circuit said lamp, and said gaseous electric relay device being thereafter operable upon cooling of said heat-responsive element to disconnect said impedance from said source and to remove the short-circuit of said lamp as well as simultaneously cause a high voltage surge from said inductance to initiate a discharge in said lamp, and a thermo-expansive element normally connecting one electrode of said gaseous electric relay device to said impedance and operable upon heating thereof to prevent short-circuiting of said lamp during its operation by the inadvertent operation of said gaseous electric relay device.

EDWARD CHARLES DENCH.
